UNITED STATES PATENT OFFICE.

EDWARD C. STEARNS, OF SYRACUSE, NEW YORK.

DESIGN FOR A CASING FOR PULLEYS.

SPECIFICATION forming part of Design No. 16,031, dated April 7, 1885.

Application filed March 10, 1885. Term of patent 7 years.

To all whom it may concern:

Be it known that I, EDWARD C. STEARNS, of Syracuse, in the county of Onondaga, in the State of New York, have invented and produced a new and original Design for a Casing for a Hay-Fork Pulley, of which the following is a specification.

This invention relates to a novel design for the casing of a hay-fork pulley; and it consists 10 of the design which will be hereinafter described and claimed, and which is represented in the accompanying drawings, in which—

Figure 1 is a side elevation of the hay-fork pulley. Fig. 2 is a front elevation of the same. 15 Like letters of reference refer to like parts in both figures.

A represents the pulley, and B the pulley-casing, provided at its upper end with a ring, b, and at the lower ends of its side plates, c, 20 with hubs d.

e represents vertical ribs extending cen-

trally on each side plate, c, from the ring b to the hub d.

f represents laterally-projecting ears formed on the side plates, c, and g represents marginal ribs or beads formed along the edges of the casing. 25

h represents openings formed in the side plates, c, on both sides of the central ribs, f, and i represents marginal ribs or beads formed 30 along the edges of the openings h.

I claim—

The design for the casing of a hay-fork pulley, consisting of side plates, c, having a ring, b, and hubs d, central ribs, e, laterally-projecting ears f, and marginal beads g, substantially as shown and described. 35

Witness my hand this 3d day of March, 1885.
EDWARD C. STEARNS.
